UNITED STATES PATENT OFFICE.

CHARLES NUHRING, OF CINCINNATI, OHIO.

FLUE-CLEANER.

No. 884,755.

Specification of Letters Patent.

Patented April 14, 1908.

Application filed December 8, 1906. Serial No. 346,868.

To all whom it may concern:

Be it known that I, CHARLES NUHRING, a citizen of the United States, residing at Cincinnati, in the county of Hamilton and State 5 of Ohio, have invented certain new and useful Improvements in Flue-Cleaners; and I do hereby declare the following to be a full, clear, and exact description of the invention, such as will enable others skilled in the art to 10 which it appertains to make and use the same.

This invention relates to improvements in flue cleaners.

The object of the present invention is to 15 provide a cleaner of the character mentioned designed for removing accumulations of soot, cinders, etc., from the flues of steam boilers by the application of a jet of steam or other fluid accompanied by a volume of air introduced simultaneously with the steam, but drawn from the surrounding atmosphere, whereby the combined mixture will effectually force out the accumulations referred to 20 without the necessity of employing scrapers and the like, as commonly practiced.

The invention further aims to provide a cleaner which is exceedingly simple, and therefore inexpensive, and one that is so constructed as to introduce a relatively large 25 volume of air with but a proportionately small volume of steam, and to provide means for enabling the steam to issue with great velocity at the point of commingling with the air, thus enabling the admixture of steam 30 and air to traverse the tubes under the most advantageous conditions for removing the accumulations therein.

With these general objects in view, and others that will appear as the nature of the 40 improvements is better understood, the invention consists substantially in the novel construction, combination and arrangement of parts, hereinafter described, illustrated in the accompanying drawings, and pointed out 45 in the appended claims.

In the drawings—Figure 1 is a side elevation of a flue cleaner embodying the herein-described invention. Fig. 2 is a longitudinal sectional view, on an enlarged scale, of 50 the cleaner head. Fig. 3 is an end view thereof. Fig. 4 is a longitudinal sectional view of the coupling head and socket for the application of the operating handle. Fig. 5 is a transverse sectional view of one end of 55 the hose coupling.

Referring in detail to the drawings, the

numeral 1 designates a cleaner head, which head is frusto-conical in form and hollow.

At the ends of the head 1 are spiders 2, which spiders are integral with the head 1, a 60 nozzle 3 which extends longitudinally of the head 1 being supported by the spiders 2 centrally of the head. It will be noted that the bore of the nozzle 3 tapers from one end to the other end, the smaller end being the discharge end of the nozzle, or that end from which the fluid under pressure issues into the particular flue of the boiler to which the cleaner is applied. By reason of the tapered bore of the nozzle 3 it is apparent that the 70 fluid under pressure will issue with great velocity from the smaller end thereof, and by reason of the spiders 2, at the ends of the head 1, an air space is formed around the nozzle 3, the air from the atmosphere drawn 75 into the larger end of the head 1 being of relatively larger volume than the volume of fluid issuing from the nozzle at the contracted end thereof. Because of the velocity of the fluid under pressure that issues from the 80 nozzle 3 a high degree of suction within the head 1 is set up, and manifestly the air following this suction is drawn into the flue, at which point it mixes with the fluid under pressure discharged by the nozzle and effectually acts upon the accumulations of soot, 85 cinders, etc. within the flue for removing the same therefrom.

It will be noted that at a point substantially midway the ends of the head 1 an inclined shoulder 4 is formed. This shoulder is provided in order that when the head is introduced into the mouth of the flue, and held 90 therein, a tight joint will be formed, thereby preventing air passing to the flue except 95 through the head 1 and around the nozzle 3.

The nozzle 3, at the larger end of the head 1, is provided with a polygonal head 5 the interior of which is threaded, and connected to said threaded end is a pipe 6, which serves 100 as a conduit for the fluid under pressure, preferably steam, that is fed to the nozzle for discharge into the flue. By reason of the shape of the head 5, it is obvious that a wrench may be readily applied thereto for 105 tightly joining the same with the pipe 6.

At the end of the pipe 6, opposite to that whereon the head 1 is applied, is a coupling head 7. This head comprises an elbow 8 to which a flexible tube 9 is applied, and the latter is connected to the head 8 through the 110 medium of a coupling 10. By reason of the

flexibility of the tube 9, which tube is connected to the source of fluid under pressure, the cleaner may be readily applied to different flues, and to permit ready manipulation 5 of the cleaner the head 8 is provided with an outwardly-extending socket 11 that extends in alinement with the pipe 6, said socket 11 receiving an operating handle 12 which is detachably connected to the socket 11 through 10 the medium of any suitable device, such as a set screw 13. It will thus be seen that through the medium of the operating handle 12, when the same is applied to the socket 11, the cleaner may be readily manipulated by 15 the operator without inconvenience or liability to injury by reason of the heated condition of the pipe 6 and the cleaner head, when steam is employed as the propulsive agent for the air.

20 The coupling 10 is formed of complementary sections 14 each of which comprises a terminal saddle 15 having clamping ears 16, and the saddles of each section are connected by bars 17. The saddles 15 at one end of the 25 coupling are smaller than the saddles at the other end, to permit application of the coupling to the coupling head 8, the saddles constituting the larger end of the coupling being applied directly to the flexible tube 9. By 30 reason of the construction described it will be seen that the tube 9 is effectually connected to the coupling head 7, and liability of separation therefrom, by reason of the pressure within the tube, reduced to a minimum. Each of the saddles 15 is provided 35 with a wedge 18 that cooperates with an inclined surface upon the opposite saddle, and consequently it will be seen that as the clamping bolts 16 are tightened the wedges 40 18 act upon said surfaces, and thus effectually bind the coupling head 7 and the flexible tube 9 in order to tightly hold the coupling 10 thereon.

In the use of the herein-described cleaner 45 the operating handle 12 is inserted in the socket 11 and fixed therein through the

medium of the set screw 13. Steam having been permitted to flow into the flexible tube 9 passes through the coupling head 7, the pipe 6, and discharges from the reduced 50 end of the nozzle 3. With the cleaner head it is applied to the mouth of the boiler flue, air is sucked into the cleaner head through the enlarged end thereof, and issuing from the smaller end the same commingles with 55 the discharged jet of steam, and this admixture passes through the flue with great velocity, forcing the accumulations of soot, cinders, etc., therefrom. The shoulder 4, as previously stated, forms a tight joint 60 between the mouth of the flue and the exterior of the cleaner head, and thereby causes atmospheric air to pass through the head and not over the exterior thereof into the flue. Thus a relatively large volume of air 65 is drawn in with but a proportionately small volume of steam, and this admixture traverses the flues under the most advantageous conditions for removing the accumulations therein.

Having thus described the invention, what is claimed as new, and desired to be secured as Letters Patent, is:

A flue cleaner, comprising a frusto-conical cleaner head the exterior of which is provided with an inclined shoulder, a nozzle arranged in said head and having one of its ends projecting beyond the head and forming a polygonal projection, spiders supporting said nozzle within said head to provide 80 an air space between the head and the nozzle, a pipe for fluid under pressure connected to said polygonal projection, a coupling head connected to said pipe and means for manipulating the cleaner.

In testimony whereof I affix my signature, in the presence of two witnesses.

CHARLES NUHRING.
